Elijah P. Penman. Rochester. New York.
Letters Patent (Design No. 118) dated 14 April 1847.

The schedule referred to in these Letters Patent and making part of the same.

To all whom it may concern Be it known that I Elijah P. Penman of the City of Rochester in the County of Monroe and State of New York have produced a new and original ornamental design for stones, and I do hereby declare that the following is a full and exact description of the same.

My production consists in a carving in two parts as shown in the accompanying specimen and in the drawing, the one part marked by the letters s, t, u, v, and the other by the letters u, v, w, x, which last described part may be divided into half and quarter sections, as indicated by the dotted lines A, B, C, D and may be so used or in whole, in combination with the part marked s, t, u, v,

What I claim as my production and desire to secure by Letters Patent is the combination of the ornamental design for stones marked s, t, u, v, in the accompanying drawing, with the ornamental design marked u, v, w, x, or with a half or quarter section thereof, made in the direction of the dotted lines A, B, and C, D.
